CLAIM

I claim the ornamental design for a cleaning apparatus with surface pattern, as shown and described.

DESCRIPTION

FIG. 1 is a top perspective view of a cleaning apparatus; FIG. 2 is a bottom perspective view of the cleaning apparatus illustrating a surface pattern;

FIG. 3 is a front side view of the cleaning apparatus illustrating the surface pattern;

FIG. 4 is a first side view the cleaning apparatus illustrating the surface pattern;

FIG. 5 is a second side view of the cleaning apparatus illustrating the surface pattern;

FIG. 6 is a top view of the cleaning apparatus;

FIG. 7 is a back view of cleaning apparatus illustrating the surface pattern; and,

FIG. 8 is a bottom view of cleaning apparatus illustrating the surface pattern.

The dashed or broken lines in FIGS. 1-7 illustrate a handle and part of the cleaning apparatus and form no part of the claimed design.

1 Claim, 8 Drawing Sheets
